AUTOMATIC CONTROL FOR HEATING SYSTEMS

William F. Miller, Evansville, Ind., assignor to Industrial Engineering Corporation, a corporation of Indiana

Application July 22, 1941, Serial No. 403,566

7 Claims. (Cl. 236—1)

The present invention relates to improvements in automatic controls for heating systems and the like and aims generally to improve existing controls by providing a positive mechanism under the control of the room thermostat or a time controlled initiator or both that will effectively, efficiently and safely deliver fuel and air to the furnace and control the burning thereof in a highly efficient manner.

One of the objects of the invention is to provide a simple and efficient control that is adaptable for the control of the burning of a variety of fuels, as for example, oil, gas or coal.

A further object of the invention is the provision of a control which is operated through one complete cycle of revolution of a controlling means, insuring positive positioning of the several supply means and the starting of each succeeding cycle.

A further object of the invention is the provision of a simplified control having positive means for regulating the time of starting and stopping the supply of fuel and air under pressure to the combustion chamber with means to change or vary the duration thereof at the will of the operator.

A further and more specific object of the invention is the provision of a control for oil burners of the so-called pot type, embodying an oil supply line and blower, in which the supply of fuel is delayed until after the operation of the burner is commenced, and is terminated substantially prior to the termination of the blower.

A further object of the invention is the provision of a control mechanism adapted for coal stokers that may be operated to supply fuel for a longer or shorter time than blower operation depending upon the grade of fuel used, thus to insure the most efficient results.

A still further object is the provision of an improved control for gas burners employing a plurality of banks or sets of gas burners to insure operation of the burners in a most efficient and desirable manner.

Many other objects and advantages of the invention will be apparent to those skilled in the art in view of the following more detailed description of one form of the invention, such as that illustrated in the accompanying drawings in which

Fig. 1 is a front elevation of the panel of the control;

Fig. 2 is a diagrammatic view illustrating one manner of wiring the associated mechanism of the control;

Fig. 3 is a diagrammatic view illustrating one

manner of employing the control for oil burners;

Fig. 4 is a diagrammatic view illustrating one manner of employing the control for coal stokers;

Fig. 5 is a similar view illustrating another manner of employing the controls for coal stokers; and

Fig. 6 is a diagrammatic view of one manner of employing the control for a plurality of banks of gas burners.

Referring more particularly to the illustrated embodiment of the invention, there is provided a panel 10 of any suitable material on which is mounted the associated mechanisms and terminal posts of the control. The panel advantageously may be mounted in a box or casing (not shown) to protect the mechanisms.

A primary controller for the burner advantageously includes a normally idle or inactive time controlled mechanism advantageously comprising an electrically operated clock motor 11 having a shaft 12 geared to a predetermined cycle of revolution and carrying primary controlling cams for the several mechanisms of the burner, such as fuel feed, blower and ignition, where electrical ignition is used. The clock motor is advantageously secured to the rear face of the panel and the shaft 12 extends through and may be journaled in the panel, so that the primary controlling cams are forwardly of the front face of the panel and accessible to the user. In the illustrated form there are two primary controlling cams fastened to the shaft, the cam 13 being formed with a recess 14 designed to control the advanced burner mechanism, for example the ignition, or blower or both, and the other cam 15 being formed with a hump 16 designed to control the delayed burner mechanism such as, for example, the fuel supply. It will be understood that these arrangements are merely illustrative and that other orders and mechanisms may be controlled as hereinafter described.

The primary controlling cam 13 controls the advanced circuit which, in the illustrated form, includes the blower and ignition circuit, through a switch 17 which has a follower 18 to close the switch as the follower rides on the outer face of the cam, and to break the switch as the follower drops into the recess 14. The controlling cam 15 controls the delayed circuit, herein illustrated as the fuel supply. Conveniently the switch 17 may be a single contact switch adapted to supply current through a switch blade 17^a to a single contact 17^b. The switches conventionally may be snap action switches of the types illus-

trated in Patent No. 1,960,020 of May 22, 1934.

The normally idle primary controller is normally under the control of an initiator circuit which includes a room thermostat. As herein illustrated the room thermostat is advantageously of the double acting type having a high thermostat at 21 and a low thermostat at 22. The high thermostat is ordinarily set to open at a temperature of from $1\frac{1}{2}$ to 2 degrees higher than the predetermined temperature setting of the thermostat 22, and is designed to prevent operation of the furnace when room temperature reaches such predetermined high degree.

The initiator circuit may also include a continuously operating time controlled mechanism 30 connected in the circuit in parallel with the room thermostat and designed to initiate operation of the primary controller at regular periodic intervals of time as will be more fully described later.

Referring to Fig. 2, the panel 10 is provided with four line voltage terminals, marked 1, 2, 3 and 4, and three secondary voltage thermostat terminals marked B, R and W, there being a transformer 40 provided for supplying the secondary voltage. The primary of the transformer is connected through wires 41-42 and line voltage terminals 1 and 2, while one side of the transformer secondary is connected by wire 43 to the thermostat terminal R and the other side is connected through wire 44, relay magnet 45 and wire 46 to thermostat terminal W.

The double acting thermostat illustrated in Fig. 2 is such as to set up a high circuit H, between terminals B and W, adapted normally to be closed and opened only when the room temperature exceeds a predetermined value above the setting of the low thermostat 22. The thermostat 22 makes and breaks the low circuit L between contacts R and W, respectively, to actuate the burner when the room temperature falls below a predetermined value and to stop the burner when temperature reaches a predetermined value as determined by the thermostat adjustment setting.

Assuming that the room temperature falls and there is a call for heat, thermostat 22 closes, completing the circuit between terminals R and W, permitting a low voltage current to flow from terminal R, wire 43, secondary of transformer 40, wire 44, relay magnet 45, wire 46 and terminal W, actuating the relay to lift the relay blade contact 47 into contact with an upper contact 48 to close the starting circuit to the primary controller motor 11. This motor circuit is as follows:

From line L' terminal 2, through wire 49 to clock motor 11, wire 50 to relay blade 47, contact 48, wire 51 to one terminal of double pole switch 18, blade 20, wire 52 to one terminal of normally open switch 17, wire 53 to line terminal 1, and line L². This circuit starts operation of the motor 11 and rotation of the primary controlling cams 13 and 15.

After completion of any burner operation, the cams 13 and 15 are always re-set and brought to rest at a predetermined position with the follower 18 of switch 17 positioned in recess 14 of cam 13 as will be described later.

The starting of the motor, as above described, rotates the cam to thereafter lift the follower 18 (see Fig. 2) and close the switch 17 to operate the advanced burner mechanisms, as for example, the blower and ignition mechanism, in the form illustrated in Fig. 3, which may be connected through wires A' and A² to line terminals 2 and 3 respectively. This circuit is from line L'

connected to terminal 2, wire A' through blower and ignition mechanism, wire A² to terminal 3, wire 54 through closed switch 17, wire 53 to terminal 1 and line L². Advantageously the blower and ignition may be operated after a lapse of about 4 seconds from the starting of the motor, in the case of an oil burner installation as illustrated in Figs. 2 and 3.

It is highly desirable, in such installations, that the blower and ignition be operated for a predetermined time prior to the admission of fuel, such as oil, so as to remove from the combustion area any undesirable gases which may remain from the previous burner operation. Accordingly, the admission of oil is controlled by a delayed circuit closed at a predetermined interval of time after the advanced circuit, as for example, approximately 10 seconds or longer after the blower and ignition are started.

The delay in closing the relay and circuit or starting the fuel supply as above described is determined by the position of the hump 16 of the cam 15 in advance of the follower 19 of the double pole switch 19 relative to the recess 14 of the cam 13. As the follower rides on the outer surface of the hump, the switch is actuated to shift the blade 20 to the opposite terminal 19^b of the double pole switch, closing the circuit from line L' terminal 2, wire F' to fuel supply valve, wire F² to terminal 4, wire 55 to double pole switch 19, blade 20, wires 52 and 53 to terminal 1 and line L².

During such time as the initiator circuits H and L remain closed and the relay magnet energized, the shifting of the switch blade 20, as above described, breaks the circuit between wires 51 and 52 which supplies current to the motor 11 and stops the motor in this position, with the follower 19^a on the high part of hump 16, maintaining both burner mechanism circuits closed, and insuring continuous burner operation until room temperature is satisfied.

When, however, the initiator circuit is broken, as when room temperature has been satisfied, the motor 11 is again actuated to complete the cycle of rotation and return the cams 13-15 to their original starting position. When breaking of the initiator circuits occurs, the magnet of the relay 45 is de-energized, permitting spring 41^a to move relay blade 47 into contact with lower contact 60, closing the motor circuit as follows: line L' wire 49, motor 11, wire 50, relay blade 47, contact 60, wire 61, wire 54, closed switch 17 wire 53 to terminal 1 and line L². This actuation of the motor 11 starts the recycling or re-setting of the primary controller to its predetermined starting position, during which time the delayed circuit controlled by the switch 19 is opened, stopping the fuel feed in the illustrated form shown in Figs. 2 and 3. During the recycling operation, the blower remains on, because the follower 18 is riding on the high surface of the cam 13, and this is of advantage in completing combustion of any fuel in the combustion pan or other products of combustion in the chamber.

The initiator circuit preferably includes, as stated above, a time controlled mechanism 30 designated to initiate operation of the primary controller at regular periodic intervals of time, and preferably includes a switch connected in the initiator circuit in parallel with the room thermostat circuit L but in series with the high circuit H.

As herein illustrated, this time-controlled mechanism includes continuously operating an electric

clock motor 30^a supplied with current through wires 31 connected to terminals 1 and 2, which in turn are connected to line wires L² and L', respectively. The motor 30^a has a shaft 32 extending through the panel 10 and on which is mounted a pair of relatively adjustable cams 33 and 34, controlling switch blades 35 and 36 as described and claimed in my prior Patent No. 2,190,603, dated February 13, 1940. Adjustment of the cams relative to each other permits variation of the duration that the switch blades are closed and thus enables the user to vary the duration of periodic operation of the furnace. The cams may be geared to motor 30^a to provide any desired time cycle of operation but I prefer, in most instances, to have the cams 32—34 make one revolution each 15 minutes, so that the initiator circuit may be closed for a variable period of from 1 to 7 minutes in each 15 minute cycle.

One of the switch contacts 36 is preferably connected by wire 37 to the terminal B of the high thermostat circuit H, and the other contact 35 is connected by wire 38 to the terminal R which is common to both circuits.

Accordingly, when the high thermostat circuit H is closed, periodic operation of the furnace is controlled by the switch contacts 35—36 to energize the relay magnet from the secondary of transformer 40 through wire 43, wire 38, contacts 35—36, wire 37 to terminal B, through closed high thermostat 21 to terminal W, wire 46, magnet 45, wire 44 to opposite sides of secondary of transformer 40. Thus when the high thermostat 21 is closed, the time controlled mechanism initiates operation of the primary controller independent of the room thermostat 22, but if room temperature is excessive, thermostat 21 opens and prevents operation of the primary controller by the time controlled mechanism.

The invention is a highly efficient control for oil burners of the pot type as illustrated in Fig. 3, though it will be readily appreciated by those skilled in the art that the invention may be effectively used in other types of furnaces.

Referring to Fig. 3, the connections between the control and the burner mechanism of a pot type oil burner are illustrated. The advanced control circuit controlled by wires A'—A² connected to terminals 2 and 3 of the panel advantageously to the blower 61 and ignition 62, when electrical ignition is used. The delayed control circuit, controlled by wire F' F² is connected to a solenoid valve 63 in the fuel oil supply line. Such lines may have a second valve (not shown) as a safety to close the line in the event of ignition failure as is customary in the art.

Assuming that the primary controlled motor 11 is geared to rotate the cams 13 and 15, one revolution in each 5 minutes, a substantial period of blower and ignition operation is provided, i. e. approximately 4½ minutes, after fuel supply is cut off, during which the combustion chamber is purged of all gases, unburned fuel and products of combustion.

The control may be effectively used in the operation of coal stokers, in which case the time-control mechanism 30 acts as a hold-fire or kindling mechanism.

In some localities the coal available for coal stoker use is relatively slow to ignite, referred to as slow ignition coal. Best results are obtained from the use of such coal if the fan is operated first, to get the coal in the retort burning briskly prior to feeding additional fuel to the rotor. Also, when the room thermostat is satisfied, the fuel

feed should be stopped but the blower should continue so as to completely ignite fuel previously fed to the retort.

In such case the burner mechanism of the stoker may be operated by my improved control by connecting the blower mechanism 65 to the advanced circuit A', A², (see Fig. 4) and the coal feed motor 66 to the delayed feed circuit F' F², where separate burners and fuel feed motors are provided in the stoker for operating the two mechanisms. Where a single motor is provided in the stoker for operating both the air and fuel feed, the delayed action of the coal feed may be effected by providing a solenoid operated clutch for the fuel feed screw, similar to the clutch 67 of Fig. 5, which is connected in the delayed circuit F' F².

When fast igniting or flash coal is available for stoker use, a different arrangement is desirable. Such coal produces a considerable amount of fly ash, and it is desirable to feed supply fuel to the retort to build up the fuel in the retort above the level of the tuyère openings to prevent blowing of the fly ash when the blower is started. When the room thermostat is satisfied, it is desirable to stop the operation of the blower, but continue the feeding of fuel to the retort for a sufficient time to again build up a sufficient bed of fuel, to prevent the fuel from being too low in the retort during the idle period.

This function may be efficiently accomplished according to the invention by connecting the coal feed in the advanced circuit A' A² and the blower in the delayed circuit F' F². When the stoker provides a single motor for operating the blower and the fuel feed, the fuel feed may be controlled by a magnetic clutch similar to the clutch 67 of Fig. 5.

Alternatively, the advanced circuit A' A² may control the fuel feed and the delayed circuit F' F² may control the actuation of a damper motor to open and close the damper.

Referring to Fig. 6, gas fired furnaces frequently include two or more sets or banks of burners. Such burners may advantageously be operated according to my invention by connecting one set or bank in the advanced circuit A' A² and the remaining sets in the delayed circuit. When the room thermostat has been satisfied, all of the burners are not cut off, the first set to be lighted remaining open during the re-setting of the primary control, so as to prevent a rapid loss of furnace temperature, providing a more even room temperature.

In the drawings I have illustrated the two cams 13 and 15 as fastened to the shaft 12, but it will be apparent to those skilled in the art that these may be relatively adjustable as in the case of the cams 33—34, in cases where it is desired to variably adjust the relative positions of the recess 14 and lobe 16 to meet different conditions of operation.

It will be apparent that while the continuously operating timer 30 is desirable, it may be omitted from the circuit, in which case the primary control operates subject only to the room thermostat in exactly the same manner as described above.

As previously stated, in stoker operation, the timer 30 acts as a hold-fire control to supply fuel to the retort periodically, for example, every fifteen minutes, and hold the fire in the retort. As this hold-fire operation should take place regardless of room temperature, it is not advisable to use a double acting thermostat which includes

the two circuits H and L. In such cases it is preferred to employ a single acting thermostat 70, the opposite sides of which are connected to the terminals R and W, while a buss bar 71 bridges the terminals B and W.

It will be readily apparent that the invention is of general application and is not restricted to the control of any specific type of heating plant nor to any particular circuit connecting the various elements of my burner mechanism. For example, though I have shown the blower and ignition connected in parallel in Fig. 3, it is obvious that the control will function as well if the several elements are connected in series.

I do not intend that the invention be limited beyond the scope of the appended claims.

I claim:

1. An automatic control for heating systems having separate fuel and air feeding mechanisms, said control comprising a normally idle controller having a predetermined position of rest, an initiator circuit including an electric motor for operating said controller and a room thermostat for initiating operation of the motor and controller, a plurality of cams on said controller, a switch mechanism controlled by one cam and electrically connected with said air feeding mechanism, a separate two-way switch mechanism controlled by another of said cams and electrically connected with said fuel feeding mechanism and to the circuit to the controller motor, said cams being arranged to initiate operation of said first-named switch and air feeding mechanism in advance of the operation of the fuel feeding switch and mechanism, said two-way switch mechanism opening the circuit to the controller motor when the fuel feeding mechanism circuit is closed to insure operation of the fuel feeding mechanism during such time as said thermostat is closed, and means under the control of the room thermostat for operating the motor to additionally rotate the controller to its predetermined normal position of rest and during such rotation sequentially break the circuit to the fuel feeding mechanism and thereafter to the air feeding mechanism.

2. An automatic control for heating systems having separate fuel and air feeding mechanisms, said control comprising a normally idle controller having a predetermined position of rest, an initiator circuit including an electric motor for operating said controller and a room thermostat and a relay adapted to be closed when room temperature falls below a predetermined value for initiating operation of the motor and controller, a plurality of cams on said controller, a switch mechanism controlled by one cam and electrically connected with said air feeding mechanism, a separate two-way switch mechanism controlled by another of said cams and electrically connected with said fuel feeding mechanism and to the circuit to the controller motor, said cam being arranged to initiate operation of said first-named switch and air feeding mechanism in advance of the operation of the fuel feeding switch and mechanism, said two-way switch mechanism opening the circuit to the controller motor when the fuel feeding mechanism circuit is closed to insure operation of the fuel feeding mechanism during such time as said thermostat is closed, and means controlled by said relay for operating the motor to additionally rotate the controller to its predetermined normal position of rest and during such rotation sequentially break the circuit to the fuel feed-

ing mechanism and thereafter to the air feeding mechanism.

3. An automatic control for heating systems having separate fuel and air feeding mechanisms, said control comprising a normally idle controller having a predetermined position of rest, an initiator circuit including an electric motor for operating said controller and a room thermostat adapted to be closed when room temperature falls below a predetermined value for initiating operation of the motor and controller, a continuously operating time controlled switch in said initiator circuit adapted to operate said electric motor at regular intervals during such times as the thermostat is open, a plurality of cams on said controller, a switch mechanism controlled by one cam and electrically connected with said air feeding mechanism, a separate two-way switch mechanism controlled by another of said cams and electrically connected with said fuel feeding mechanism and to the circuit to the controller motor, said cams being arranged to initiate operation of said first-named switch and air feeding mechanism in advance of the operation of the two-way switch and fuel feeding mechanism, said two-way switch mechanism opening the circuit to the controller motor when the fuel feeding mechanism circuit is closed to insure operation of the fuel feeding mechanism during such time as said thermostat is closed, and means under the control of the room thermostat for operating the motor to additionally rotate the controller to its predetermined normal position of rest and during such rotation sequentially break the circuit to the fuel feeding mechanism and thereafter to the air feeding mechanism.

4. An automatic control for heating systems having a plurality of electrically operated mechanisms subject to the initial control of a room thermostat responsive to temperature requirements, said control comprising a normally idle controller, an initiator circuit including an electric motor means for operating the controller, said initiator circuit adapted to be closed to respond to room temperature requirements for initiating operation of the motor and controller, a continuously operating time controlled switch in said initiator circuit adapted to operate said electric motor at regular intervals of time, a plurality of cams on said controller, a separate switch mechanism controlled by each cam, said cams being arranged to operate said switch mechanisms in sequential order, separate electric connecting means adapted to be connected to the individual electrically operated mechanisms of a heating system, said separate connecting means being connected with the individual cam controlling switch mechanisms for independent sequential control of the individual electrically operated mechanism of the same heating system, one of said switch mechanisms being two-way and arranged to halt operation of the controller motor to insure operation of the same heating system during such time as room temperature requirements are unsatisfied, and means under control of the initiator circuit for operating the motor to reset the controller to its normal idle position and to deenergize the circuits to the separate electric connecting means in the reverse sequential order to their initial energizing.

5. An automatic control for heating systems having a plurality of electrically operated mechanisms subject to the initial control of a room thermostat responsive to temperature requirements, said control comprising a normally idle

controller, an initiator circuit including an electric motor means for operating the controller, said initiator circuit adapted to be closed to respond to room temperature requirements for initiating operation of the motor and controller, a plurality of cams on said controller, a separate switch mechanism controlled by each cam, said cams being arranged to operate said switch mechanisms in sequential order, separate electric connecting means adapted to be connected to the individual electrically operated mechanisms of a heating system, one of said switch mechanisms being two-way and arranged to halt operation of the controller motor to insure operation of the same heating system during such time as room temperature requirements are unsatisfied, and means under control of the initiator circuit for operating the motor to reset the controller to its normal idle position and to deenergize the circuits to the separate electric connecting means in the reverse sequential order to their initial energizing.

6. An automatic control for heating systems having a plurality of electrically operated mechanisms subject to the initial control of a room thermostat responsive to temperature requirements, said control comprising a normally idle controller, an initiator circuit including an electric motor means for operating the controller, said initiator circuit adapted to be closed to respond to room temperature requirements for initiating operation of the motor and controller, a plurality of cams on said controller, a single pole switch controlled by one of said cams and adapted to be connected to an electrically operated mechanism of a heating system, a double pole switch controlled by another of said cams and having one pole thereof interposed in the initiator circuit to the controller motor and the other pole adapted to be connected to a separate electrically operated mechanism of the same heating system, said cams being arranged to operate said switches in sequential order for independent sequential control of the individual electrically operated mechanisms of the same heating system, said double pole switch being ar-

5 ranged to halt operation of the controller motor upon contact with the other pole thereof to insure operation of the same heating system during such times as room temperature requirements are unsatisfied, and means under control of the initiator circuit for operating the motor to reset the motor to its normal idle position and to reverse the position of said cam controlled switches.

10 7. An automatic control for heating systems of the type having a plurality of electrically operated mechanisms subject to the initial control of a room thermostat responsive to temperature requirements, said control comprising a normally idle controller having a predetermined normal idle position of rest, an initiator circuit including an electric motor for operating the controller and a switch, a relay for operating said switch and adapted to be connected to a room thermostat and to be energized in response to room temperature requirements, said controller including a plurality of cams, a switch mechanism controlled by one of said cams and adapted to be connected to an electrically operated mechanism of a heating system, a two-way switch mechanism controlled by another of said cams, and adapted to have one of its contacts connected to a separate electrically operated mechanism of the same heating system and the other contact of said two-way switch being connected to said relay operated switch, said cams being arranged to operate the switch controlled thereby in a certain sequential order, said two-way switch mechanism serving, in one position, to close the circuit to the controller motor when the relay operated switch is closed and in the other position to break said motor circuit and insure continued operation of the electrically operated mechanisms of the same heating system during such time as the relay is energized, and means for operating the motor when the relay is deenergized to reset the controller to position the cams in their normal predetermined position of rest.
